UNITED STATES PATENT OFFICE.

JOSEPH P. BADER, OF NEW YORK, N. Y., ASSIGNOR TO THE TEXAS COMPANY, OF NEW YORK, N. Y., A CORPORATION OF TEXAS.

COLORIMETER.

Application filed December 21, 1921. Serial No. 523,819.

This invention relates to improvements in colorimeters or instruments for making tests to determine the color values of various materials particularly of gasoline, 5 kerosene, lubricating oil or other products of petroleum.

One object of the invention is to provide improved means for the examination and color analysis of liquids of the character 10 described.

Another object relates to the provision of testing equipment whereby the color values of liquid being tested may be compared to definite standards.

15 Another object relates to the provision of means whereby the color code combination may be indicated and may be read off in a minimum of time.

Other objects will appear from the following description of the invention taken 20 in connection with the drawings, in which

Fig. 1 is a transverse section of a cabinet within which the colorimeter of my invention may be applied,

25 Fig. 2 is an end elevation of the colorimeter with parts broken away.

Fig. 3 is a section taken on the line 3—3 of Fig. 2,

Fig. 4 is a plan view of the colorimeter,

30 Fig. 5 is a horizontal section taken on the line 5—5 of Fig. 2, and

Fig. 6 is a section taken on the line 6—6 of Fig. 5.

Like reference characters denote like 35 parts in the several figures of the drawings.

Referring to Fig. 1 of the drawings there is shown one embodiment of my invention applied to a light cabinet comprising a suitable table 10 and a cabinet

40 11 made of wood and suitably panelled to provide access to the interior thereof. In the upper portion of the interior of the cabinet there is mounted in any suitable manner a source of light 12 of conventional

45 design containing a suitable electric light bulb (not shown) supplied by current from a pair of conductors such as 13. The source of light 12 includes a reflector adapted to throw the light upon a reflecting screen 14

50 mounted upon a wall of the cabinet 11 and arranged to throw reflected light into the colorimeter. The opposite wall is provided with an aperture or peep-hole through

55 which projects an eye-piece 15 forming a part of the colorimeter.

The colorimeter comprises a tripod or metal stand 20 and a pair of spaced supports 21 for supporting the base 22. As clearly shown in Fig. 3 one end of the base 22 is provided with a pair of spaced parallel upright flanges 23 and 24, to one of which is secured the eye-piece 15. A portion of each of the flanges extends laterally to one side of the base 22 (see Fig. 4) thus forming a support for a bearing 25 for a pair of rotatable members or wheels 26 and 27. The upright flange 24 is hollow and positioned therein is a plurality of mirrors such as 30 and 31, whereby parallel rays of light such as 32 and 33 may be diverted into the 60 single eye-piece 15 (see Fig. 5). It is understood, however that the prisms shown may be replaced by suitable mirrors or other equivalent devices. The rays of light collectively indicated by the broken line 75 designated 33 are reflected from the screen 14 and are passed through the material being tested which may be contained in a suitable translucent container such as 34 or may be contained in a relatively large container 35 shown by the dotted lines in Fig. 1. The arrangement of the wheels 26 and 27 is such that the rays of light collectively indicated by the broken line designated 32 and reflected from the screen 14 pass 80 through screens provided near the periphery of the wheels. An opaque partition 36 is provided for separating the light rays 32 and 33 and for preventing leakage of the 85 light.

Each of the wheels 26 and 27 is provided with a plurality of apertures such as 40 and 41 and mounted in each aperture is a color screen such as 42. The several color screens of the wheel 26 are differently characterized with respect to color, and their characteristics are preferably widely different from each other. The color screens of the wheel 27 are also different from each other but in this case, different from each other by relatively small degrees of difference. The edges of the wheels are notched and a roller 43 is secured to a spring member 44 and forms in combination with these notches impositive stops for maintaining the wheels in definite positions. The wheel 27 is provided with a plurality of apertures 45 through which may be observed a number of plates 46 appearing on the face of the wheel 26. A suitable peep-hole or 100 105 110

window may be provided in the well of the cabinet 11 whereby the operator may look through the aperture 45 and observe the code indication on the wheel 26. As indicated in Fig. 2 an additional code is placed upon the surface of the wheel 27 and the two codes in combination indicate the combination of color screens which are in use. A pointer 47 is provided for indicating the code combinations which are to be read.

In operation a suitable quantity of liquid to be tested is placed in a container such as 34 or 35 and the source of light 12 is made active. The observer places his eye in front of the eye-piece 15 and rotates the wheels 26 and 27 until he obtains the same color as a result of the light rays passed through the color screen as is the case with the rays passed through the liquid. The arrangement is such that the field of vision observed through the eye-piece is divided into two equal portions one of which is affected by the rays passed through the color screens and the other of which is affected by the rays passed through the liquid to be tested. Thus accurate observations may be made and the color characteristics of a liquid may be determined in terms of color codes as represented by the numerals observed opposite the pointer 47 when the color tints are balanced. It will be noted that the readings may be taken practically instantaneously and that the operator may modify the color screens used very quickly by merely manipulating the wheels.

Apparatus of preferred form and construction has been illustrated and described for the purpose of showing a way in which this invention may be practiced, but the inventive thought upon which this application is based is broader than this illustrative embodiment. It is therefore understood that the scope of the invention is not to be limited by the present disclosure, reference being had to the appended claims for that purpose.

What is claimed is:

1. A colorimeter comprising in combination, a source of light, a plurality of rotatable wheels each provided with a plurality of color screens of varying color characteristics, each of said wheels having designated numbers applied to one face thereof and one of said wheels having a plurality of apertures for observing the numbers on the face of the other wheel, means for directing sundry rays of light through the object being tested and other rays through certain of the color screens in said wheels, and a single means for observing said rays of light in proximity.

2. A colorimeter comprising a source of light, a plurality of rotatable disks provided with color screens, an eye-piece, means for

separating the rays of light projected from said source and passing some of said rays through an object being tested and others through certain of the color screens, and means for subsequently converging the separated rays to meet in juxtaposition upon a common field of vision before the eye-piece.

3. A colorimeter comprising a plurality of rotatable disks, each provided with color screens of varying characteristics, means for projecting a plurality of light rays from a common source, means for controlling the direction of projection of said rays whereby some rays pass through the object being tested and others pass through one or more of the color screens, and means for converging by reflection all of said light rays in proximity.

4. A colorimeter comprising in combination, a source of light, a plurality of adjustable color screens, an eye-piece, means for separately projecting sundry rays of light through the material being tested and other rays through a selected combination of color screens, and for subsequently converging the rays of light to meet in juxtaposition upon a common field of vision before said eye-piece.

5. A colorimeter comprising an eye-piece, a plurality of rotatable wheels each provided with a series of color screens of varying characteristics, a source of light, means for simultaneously passing some of the rays of light from said source through an object being tested and other rays through certain of the color screens, and means including a plurality of mirrors for subsequently diverting the several rays of light into the eye-piece for comparison.

6. A colorimeter comprising a source of light, an eye-piece, a plurality of rotatable wheels each provided with a series of color screens of varying characteristics, means for simultaneously projecting certain of the rays of light from said source through the object being tested and other rays through a selected combination of color screens, arbitrarily chosen marks for identifying the particular color screens through which light is passing, and means for subsequently diverting all of said light rays to meet upon a common field of vision before said eye-piece.

7. A colorimeter comprising in combination, a source of light, means for directing independent rays thereof in separated paths in one of which is disposed the object being tested, adjustable means for selectively interposing certain of a plurality of graded color screens in the other path of light rays, and means for converging the separated light rays by reflection to meet in juxtaposition on a common field of vision.

In witness whereof I have hereunto set my hand this 17th day of December, 1921.

JOSEPH P. BADER.
